2 SHEETS-SHEET 2.

UNITED STATES PATENT OFFICE.

LAWRENCE GRIFFITH, OF YONKERS, NEW YORK.

INSULATED RAIL-JOINT.

1,052,244.

Specification of Letters Patent.

Patented Feb. 4, 1913.

Application filed July 25, 1912. Serial No. 711,485.

To all whom it may concern:

Be it known that I, LAWRENCE GRIFFITH, a citizen of the United States, and resident of the city of Yonkers, county of Westchester, and State of New York, have invented certain new and useful Improvements in Insulated Rail-Joints, of which the following is a specification.

One of the main objects of this invention 10 is to provide a rail joint which may be used in connection with tie plates under the rail ends and without the necessity of placing insulating material between said tie plates and the rails.

15 It is the common practice in insulated rail joints where tie plates are used to insert a strip of fiber or other suitable hard insulating material between the rail base and the tie plate. This is objectionable for 20 the reason that the insulation is soon disintegrated and destroyed by the constant hammering or pounding of the rail thereon. It is manifest, therefore, that to provide an efficient insulated rail joint in which tie 25 plates may be used, said plates and the rails being in direct contact, is very desirable. The use of tie plates has become practically universal in modern railroad building and it becomes practically necessary, therefore, 30 to use tie plates under the rail joints.

Another object of the invention is to provide a tie plate especially adapted for improved rail joint construction.

Another object of the invention is to so 35 construct the joint that it serves as a rail anchor to prevent longitudinal movement or "creeping" of the rails.

There are other important objects and 40 advantages of the invention which will appear hereinafter.

In the drawings, Figure 1 is a transverse sectional view on the line I—I of Fig. 3; Fig. 2 a similar view on the line II—II of Fig. 3; Fig. 3 a plan view of the joint; Fig. 4 a side elevation thereof; Fig. 5 a transverse sectional view on the line V—V of Fig. 7; Fig. 6 a similar view on the line VI—VI of Fig. 7; Fig. 7 a plan view of a modified form of the joint; and Fig. 8 a 50 side elevation thereof.

Referring to the various parts by numerals, 1 and 2 designate the rail ends which are separated by the insulation 3. Under the rail 1 is placed a tie plate 4, and under 55 rail 2 is placed a tie plate 5. Under the heads of the rails and bridging the joint be-

tween them are placed wearing pieces 6 which bridge the joint between the rail ends and extend throughout the length of the joint. These wearing pieces are outwardly 60 tapered in cross section so that they are substantially wedge shape, their thickest portion being adjacent the rail web so that they cannot be laterally or outwardly displaced by the vibrations of the rails. The 65 under sides of these wearing pieces are downwardly and inwardly inclined and bear directly on the correspondingly inclined upper surfaces of the splice-bars 7 so that as the splice-bars are adjusted inwardly 70 these wearing pieces are moved upwardly.

Each wearing piece is formed at each of its end with a downwardly extending locking flange 8 which is adapted to engage the ends of the splice-bars to prevent any material longitudinal movement of said wearing pieces. The wearing pieces and the splice-bars are insulated from the rail ends by the insulation 9 which fits closely against the rails and lies between the wearing pieces 80 and the heads of the rails, and between the splice-bars and the bases of the rails, so that the wearing pieces and the splice-bars are insulated from both rails, said insulation extending throughout the length of the 85 joint. The base flanges 10 of the splice-bars extend outwardly a considerable distance beyond the edges of the rail bases, for a purpose which will hereinafter appear. The joint bolts 11 are insulated from the 90 rails and the splice-bars in the usual manner. The inner edges of the wearing pieces fit closely against the webs of the rails so that there is practically no inward movement of said wearing pieces during the inward adjustment of the splice-bars. Of course, the splice-bars hold the wearing pieces closely against the insulation and the movement of said wearing pieces during adjustment will be only sufficient to take up 95 100 the wear on the insulation and to firmly clamp the insulation against the rails.

The rail ends rest directly on the tie plates 4 and 5 with no insulating material interposed between them. It is necessary, therefore, that the tie plate under one rail shall be insulated from one of the splice-bars, the tie plate under the other rail end being insulated from the other splice-bar. To accomplish this in a simple manner and without the use of insulating material, I extend 105 110 the base flanges of the splice-bars a consid-

erable distance beyond the longitudinal edges of the rail bases, as previously described. As shown in Fig. 1, the base flange of one splice-bar extends outwardly beyond the longitudinal edge of one tie plate and said splice-bar is secured to the tie by means to spikes 12 which do not contact with the tie plate. The base flange at the other end of the splice-bar is formed with spike-receiving recesses 13 through which spikes 14 are driven.

The tie plates directly below the slots 13 are formed with apertures 14^a through which the spikes may pass.

15 Each tie plate is formed with a longitudinally extending upstanding flange 15 close to one of its edges, which flange is adapted to engage the longitudinal edge of the rail base. Each tie plate 20 is also formed with a longitudinal flange 16 on the opposite or reverse side thereof from the flange 15, this latter flange being parallel with flange 15 and placed a short distance inwardly from the edge of 25 the plate near which said flange 15 is located. These flanges or shoulders are formed on the tie plates for the purpose of resisting the outward thrust on the rails, and when in use, one or the other flange is 30 placed in contact with the outer edge of the rail base. In applying these tie plates to the joint, the shoulder 15 of one tie plate is brought against the outer edge of the base flange of one rail and the shoulder 16 35 of the other tie plate is brought against the outer edge of the base of the other rail. The base flanges of the splice-bars extend outwardly beyond the edges of the rail bases and beyond the edge of the tie plate when 40 flange 15 is in engagement with the outer edge of the rail base, and may be secured directly to the tie by spikes 12 without the spikes contacting with the tie plate. The result of this is that the said tie plate is not 45 electrically connected to the splice 10, although it is in direct contact with the rail base. The other tie plate arranged under the other rail end is so disposed that its flange 16 contacts with the outer edge of 50 the rail base and the spikes 14 pass through the base flange of the splice-bar and through apertures in the tie plate. The tie plates are of such width that they do not contact with the spikes or other fastening means except 55 where said fastening means pass directly through them. The inner or unflanged edge of the tie plate is provided with apertures 17 through which the spikes which pass through the splice-bars are driven when flange 15 is 60 in contact with the rail base, as shown in Fig. 2.

It is manifest that with this arrangement of the tie plates and splice-bars it will only be necessary to insulate the splice-bars from 65 one rail. It is manifest that the spikes 14

electrically connect the splice-bar and tie plate through which they pass and likewise said parts to the rail resting on the tie plate. It is, therefore, clear that it is not necessary to place insulation between the splice-bar and the rail end thus electrically connected. However, in practice it is probable that insulation will be placed as shown in the drawings in order to simplify the manufacture and assembling of the joints.

70 By providing a tie plate with the two flanges 15 and 16 formed thereon said plates may be formed by one set of rolls and the depending flange will enter the wood of the tie and act or serve as an anchoring flange. By 80 providing the two flanges near one edge of the plate the said plate is practically universal in its application to rails of various widths.

85 From the foregoing it is manifest that one splice-bar will be completely insulated from one tie plate and that the other splice-bar will be similarly insulated from the other tie plate. As shown in the drawings, tie plate 4 is not engaged by the spikes 12 which 90 secure the splice-bar flange 10 to the tie, but said tie plate is engaged by the spikes 14 which pass through the splice-bar and tie plate. The spikes 14 are arranged on opposite sides of the joint between the rail 95 ends and on opposite sides of the rails so that they are diagonally opposite each other. The same is true of the spikes 12. It is, therefore, manifest that while I use a tie plate under each rail end and bring the rail 100 in direct contact with it, no electric current can find its way around the joint.

105 In the construction shown in Figs. 5 to 8 inclusive, each tie plate is formed with a longitudinally extending upstanding flange 15^a which engages the edge of the rail base, and with a similarly extending flange 16^a on its opposite edge which engages the longitudinal edge of the base flange of the splice-bar, the said flange 16^a being arranged adjacent to the apertures 14^b and the slots 13 in the splice-bar. The flange 15^a terminates short of the longitudinal edge of the adjoining splice-bar so that it will not be engaged by the spikes 12 which are arranged to clamp the longitudinal edge of said splice-bar. The spikes 14 pass through the splice-bars and through the tie plates, thereby serving as a means to anchor both the tie plate and the splice-bar to the tie. As the joint bolts 11 rigidly connect the splice-bars with the rails it is manifest that the rail joint structure forms an efficient rail anchor to prevent the longitudinal creeping of the rails.

110 120 125 It is manifest that in both of the constructions shown in Figs. 1 to 4 inclusive, and in Figs. 5 to 8 inclusive, only one form of tie plate is used. The tie plate shown in Figs. 1 to 4 inclusive may be used under either 130

rail end, and may be used either side up. By placing the flange or shoulder 16 in engagement with the edge of the rail base the splice-bar will project very slightly beyond the opposite edge of the base. This permits 5 the spikes 12 to be passed through the splice-bar and into the tie without engaging the tie plate. When the shoulder 15 is placed in engagement with the edge of the rail base 10 the spikes 12 may be driven into the tie without engaging the shouldered end of the tie plate. It is, therefore, clear that by placing one or the other surface of the tie plate uppermost the said plate will project beyond 15 the rail a greater or less distance, on one side or the other, as may be necessary to secure the proper insulation of the tie plates. This is of advantage for the reason that the tie plates may be formed by one set of rolls. 20 It is also manifest that the tie plate shown in Figs. 5 to 8 inclusive may be adapted for use under either rail end by reversing it, this reversal being secured by horizontally 25 rotating the tie plate. In the construction shown in Figs. 1 to 4 inclusive, I have shown the splice-bars formed with three spiking slots 13 while in Fig. 6 the splice-bars are shown with only two spiking slots 13a. It is, of course, manifest that the number of 30 these slots may be varied as desired.

What I claim is:

1. An insulated rail joint comprising a pair of splice-bars, means for insulating said splice-bars from rail ends, a pair of tie plates, one for each rail end, and means for securing one end of each splice-bar to a tie, said means being out of contact with the adjoining tie plate. 35 2. An insulated rail joint comprising a pair of splice-bars formed with outwardly extending base flanges, means for insulating said splice-bars from rail ends, a pair of tie plates, one for each rail end, the base flange of one splice-bar extending outwardly beyond the longitudinal edge of one tie plate and the base flange of the other splice-bar extending outwardly beyond the longitudinal edge of the other tie plate, fastening means adapted to secure the splice-bars to the ties without passing through the tie plates and fastening means adapted to pass 40 through the splice-bars and the tie plates. 45 50

3. An insulated rail joint comprising a pair of splice-bars formed with outwardly extending base flanges, means for insulating said splice-bars from rail ends, a pair of tie plates, one for each rail end, the base flange of one splice-bar extending outwardly beyond the longitudinal edge of one tie plate and the base flange of the other splice-bar extending outwardly beyond the longitudinal edge of the other tie plate, fastening means adapted to secure the splice-bars to the ties without passing through the tie plates, fastening means adapted to pass 55 60 65

through the splice-bars and the tie plates, and longitudinally extending upstanding flanges carried by the tie plates and adapted to engage the longitudinal edges of the rail bases. 70

4. An insulated rail joint comprising a pair of splice-bars formed with outwardly extending base flanges, means for insulating said splice-bars from rail ends, a pair of tie plates, one for each rail end, the base flange of one splice-bar extending outwardly beyond the longitudinal edge of one tie plate and the base flange of the other splice-bar extending outwardly beyond the longitudinal edge of the other tie plate, fastening means adapted to secure the splice-bars to the ties without contacting with the tie plates, fastening means adapted to pass through the splice-bars and the tie plates, and longitudinally extending upstanding flanges carried by the tie plates and adapted to engage the longitudinal edges of the base flanges of the splice-bars. 75 80 85

5. In an insulated rail joint, the combination of the meeting ends of two rails, splice-bars, wearing pieces between the splice-bars and the rail heads, insulating material between the wearing pieces, splice-bars and the rails, the splice-bars being formed with base flanges extending outwardly beyond the longitudinal edges of the rails, a tie plate under each rail end, means for securing one end of each splice-bar to a tie, and means for securing the other end of said splice-bar to a tie out of contact with the adjoining tie plate, whereby one end of each splice-bar will be insulated from one tie plate. 90 95 100

6. In an insulated rail joint, the combination of the meeting ends of two rails, splice-bars, insulating material between the splice-bars and the rails, the splice-bars being formed with base flanges extending outwardly beyond the longitudinal edges of the rails, a tie plate under each rail end, means for securing one end of each splice-bar to a tie, and means for securing the other end of said splice-bar to the tie out of contact with the adjoining tie plate, whereby one end of each splice-bar will be insulated from one tie plate. 105 110 115

7. In an insulated rail joint the combination of the meeting ends of two rails, splice-bars formed with base flanges extending outwardly beyond the longitudinal edges of the rails, wearing pieces between the splice-bars and the rail heads, said wearing pieces being wedge shape in cross section and tapering outwardly, a tie plate under each rail end, means for securing one end of each splice-bar to a tie, and means for securing the other end of said splice-bar to a tie out of contact with the adjoining tie plate, whereby one end of each splice-bar will be insulated from one tie plate. 120 125 130

8. In an insulated rail joint the combination of the meeting ends of two rails, splice-bars formed with base flanges extending outwardly beyond the longitudinal edges of the rails, wearing pieces between the splice-bars and the rail heads, said wearing pieces being wedge shape in cross section and tapering outwardly and bridging the joint between the rails, a tie plate under each rail end, means for securing one end of each splice-bar to a tie, and means for securing the other end of said splice-bar to a tie out of contact with the adjoining tie plate, whereby one end of each splice-bar will be insulated from one tie plate.
9. An insulated rail joint comprising a pair of splice-bars formed with outwardly extending base flanges, means for insulating said splice-bars from the rail ends, a pair of tie plates one for each rail end, the base flange of one splice-bar extending outwardly beyond the adjoining longitudinal edge of one tie plate, and the base flange of the other splice-bar extending outwardly beyond the adjoining longitudinal edge of the other tie plate, fastening means adapted to secure the splice-bars to the ties without contacting with the tie plate, longitudinally extending flanges on the tie plate, one on each side of and at different distances inwardly from one longitudinal edge of said plate, whereby both tie plates may be of the same construction and adapted for use under either rail end.
10. In an insulated rail joint, the combination of the meeting ends of two rails, a tie plate under each rail end and in electric contact therewith, a pair of splice-bars, means for insulating one splice-bar from one rail end and the electrically connected tie plate, and means for insulating the other splice-bar from the other rail end and its electrically connected tie plate, the tie plates being arranged in a staggered relation with respect to the center line of the rail, for the purpose set forth.
11. In an insulated rail joint, the combination of the meeting ends of two rails, a tie plate under each rail end and in electric contact therewith, each tie plate being formed on opposite sides with rail-engaging
- shoulders in vertical planes separated a suitable distance from each other and from the parallel edges of the plate, a pair of splice-bars, and means for insulating one splice-bar from one rail end and the electrically connected tie plate, and means for insulating the other splice-bar from the other rail end and its electrically connected tie plate.
12. In an insulated rail joint, the combination of the meeting ends of two rails, a tie plate under each rail end and in electric contact therewith, a pair of splice-bars and means for insulating one splice-bar from one rail end and the electrically connected tie plate, means for insulating the other splice-bar from the other rail end and its electrically connected tie plate, the tie plates being reversible, and arranged in a staggered relation, substantially as described and for the purpose set forth.
13. In an insulated rail joint, the combination of the meeting ends of two rails, splice-bars formed with base flanges extending outwardly beyond the longitudinal edges of the rails, metallic wearing pieces between the splice-bars and the rail heads, a rail support under each rail end, means for securing one end of each splice-bar to a tie, and fastening devices for securing the other end of each of said splice-bars to a tie without contacting with the adjoining rail support, whereby one end of each splice-bar will be insulated from one rail support.
14. An insulated rail joint comprising a pair of splice-bars, means for insulating said splice-bars from the rail ends, a pair of tie plates, one for each rail end, means for securing one end of each splice-bar to a tie, said means being out of contact with the adjoining tie plate, and longitudinally upstanding flanges carried by the tie plates and adapted to engage the longitudinal edges of the rail bases.

In testimony whereof I hereunto affix my signature in the presence of two witnesses.

LAWR. GRIFFITH.
